RECTIFIER

Charles A. Escoffery, East Orange, N. J., assignor
to Federal Telephone and Radio Corporation,
New York, N. Y., a corporation of Delaware

Application July 22, 1947, Serial No. 762,694

2 Claims. (CL 175—366)

1

My invention relates to rectifiers and is particularly directed to structural improvements in rectifiers of the dry-plate semi-conductor type.

It has been proposed to apply successive layers of base metal, semi-conducting metal, and counterelectrode to a rod. While such a rod-type rectifier has excellent electrical characteristics, it may be damaged, in certain industrial applications, by abrasion of the rather thin and fragile layers of material on the rod. The layers, further, may corrode readily in some atmospheres, while in other cases, the electrical characteristics of the rectifier may be impaired by exposure to certain substances, such as mercury or mercury vapor.

One object of my invention is to provide improved means for enclosing and protecting rod-type rectifiers.

Another object is to provide a protecting covering for rod-type rectifiers which both mechanically and chemically shields the coated materials of the rectifier, which is rugged in construction yet relatively inexpensive, and which is compact and pleasing in appearance.

The scope of my invention is defined with particularity in the appended claims and preferred embodiments, which are described in the following paragraphs and shown in the accompanying drawing, in which:

Fig. 1 shows in longitudinal section, one rod-type rectifier of my invention, and

Figs. 2 and 3 show in elevation, and partly in section, alternative rod-type rectifiers of my invention.

The particular rectifier contemplated here comprises a core rod 1, either solid or hollow, with an outside surface composition suitable for the electrical base of semi-conductor materials. For lightness and strength, aluminum serves well as rod metal, while iron, nickel, or cobalt is desirable as base metal for the semi-conductor. Accordingly, I recommend an aluminum rod plated with one of the ferrous metals, nickel being easy to deposit electrolytically. The semi-conductor material 2 is preferably metallic selenium, which also may be electro-deposited from suitable electrolytes. One end of the rod is uncoated with the semi-conducting layer so that electrical connection may be made to the rod. The semi-conductor is then covered with a counterelectrode layer 3, a low melting alloy being preferred such as commercial "Woods" metal, or an alloy of cadmium, tin, bismuth, and lead, which has a melting point below the semi-conductor metal. The constituents of the mentioned alloy are so

2

proportioned as to melt below about 200 degrees centigrade so that it may be applied in the molten state, as by dipping, to selenium without melting the selenium. Selenium melts at about 217 degrees centigrade.

According to my invention, the ends of the coated rod are enclosed in terminal caps 4 and 5 which electrically contact the base metal and the counterelectrode, respectively. The caps accordingly comprise the two electrical terminals of the rectifier, and may conveniently be connected in circuit by pressing the caps into holders of the type used for cartridge fuses. Lead wires may of course be soldered or welded to the caps if desired. The cap 4 on the uncoated end of the rod is secured in place by tinning the interior of the cap and soldering directly to the rod, and the cap 5 on the counterelectrode may be crimped lightly to bind it in place without fracturing the underlying coatings.

Finally, the edges of the caps are sealed and the counterelectrode and semi-conductor layers are covered with a quite heavy protective coating 6 of non-conducting paint or enamel. A resin base thermoplastic may, alternatively, be applied, or any non-porous non-conducting material which will adhere to metal may be used. A still further alternative may comprise a wrapping of thin raw rubber that is vulcanized in place. The protective coating contemplated here will not harden and crack or chip with age but will remain sufficiently plastic to maintain the hermetic seal at the edges of the caps.

The caps may be exteriorly polished or plated with rust resisting metal for good contacting surfaces, and the protective and sealing coat may be appropriately colored, if desired, to indicate rectifier capacity. The finished rectifier is mechanically rugged, is hermetically sealed, is pleasing in appearance, and most important, is relatively inexpensive in construction. My rectifier is adapted for manufacture by high-speed automatic processes, little hand work being required. The semi-conducting and counterelectrode layer are plated continuously and the caps, of the inexpensive drawn type, may be rapidly crimped and soldered in place. Painting and drying can of course be performed on a conveyor.

In Fig. 2, the cap 5 on the coated end of the rod is extended over the counterelectrode to the edge of the counterelectrode plating and the cap 4 on the rod is extended to near the edge of the semi-conducting layer. The exposed edges of the rod platings 2 and 3 between the caps are

then covered with the protective and sealing coat 6, as in Fig. 1. The coat, in this embodiment, is a comparatively narrow band of paint or plastic around the rectifier.

In applications where a uniform diameter throughout the length of the rectifier cylinder is not important, the cap 4 may be omitted as suggested in Fig. 3 and the bared end of the rod 1 may serve as one terminal of the rectifier. The protective coating 6 seals the rim of the cap 5 and covers the exposed edges of the semi-conducting layer 2 and the counterelectrode alloy 3. Again, simplicity, hermetic sealing, ruggedness, and neat appearance characterize my novel rectifier.

I claim:

1. A rectifier comprising a metal rod, a semi-conducting layer of selenium substantially covering said rod, one end only of said rod being exposed, a counterelectrode alloy substantially covering said semi-conducting layer with the edge only of said semi-conducting layer being exposed, a metal cap fitted over the end of said rod carrying said counterelectrode coating, and a protective insulating coating on said rod from the rim of said cap to near the end of the mentioned exposed portion of the rod.

2. A rectifier comprising a rod, successive layers of semi-conducting and counterelectrode materials on said rod and extending from one end to near the other end of said rod, a deep cap telescoped over said one end and substantially enclosing the counterelectrode layer, and a hermetic seal between the rim of said cap and said rod.

CHARLES A. ESCOFFERY.
